UNITED STATES PATENT OFFICE.

JOHN ZIMMERMAN, HARRY C. ZIMMERMAN, GEORGE S. ZIMMERMAN, AND FREDERICK WILKER, OF TAVISTOCK, ONTARIO, CANADA.

FEEDING ATTACHMENT FOR TONGUING AND GROOVING MACHINES.

1,121,707.

Specification of Letters Patent. Patented Dec. 22, 1914.

Application filed May 23, 1914. Serial No. 840,516.

To all whom it may concern:

Be it known that we, JOHN ZIMMERMAN, HARRY C. ZIMMERMAN, GEORGE S. ZIMMERMAN, and FREDERICK WILKER, all of the village of Tavistock, in the county of Oxford, in the Province of Ontario, Canada, have invented certain new and useful Improvements in Feeding Attachments for Tonguing and Grooving Machines, of which the following is the specification.

Our invention relates to feeding attachments for tonguing and grooving machines and is particularly adaptable to that type of machine known in the trade as the "Linderman dove-tailer and groover" in which the board portions are fed simultaneously from both ends of the machine toward the center to be simultaneously operated upon, and the object of the invention is to provide a feeding attachment whereby boards of various widths may be fed in pairs from one point intermediately of the length of the tonguing and grooving machine to the ends of the machine, one board of each pair passing to one end of the machine and the other board to the other end and whereby the boards are there transferred laterally on to the conveyers of the grooving machine, and it consists essentially of a table supported in position flush with the table of the tonguing and grooving machine, a longitudinal guide strip extending from each side of the center and in proximity to each side of the feeding table, an adjustable hopper located between the inner ends of the aforesaid strip and conveyer chains revolving in the opposite directions to each other, one chain being located in proximity to each guide strip and designed to carry the board from the center of the machine to the receiving point of the tonguing and grooving machine, resilient means for holding the boards carried in the conveyers against the guiding strips and means for then passing the board laterally into the conveyer of the tonguing and grooving machine as hereinafter more particularly explained by the following specification.

Figure 1, is a side elevation of a tonguing and grooving machine showing our attachment in position beside the same. Fig. 2, is a plan view of Fig. 1. Fig. 3, is a sectional elevation of the center portion of the feeding table showing the chain conveyers for carrying the boards longitudinally. Fig.

4, is a plan view of the parts shown in Fig. 3. Fig. 5, is a cross sectional view on line $x-y$ Fig. 3. Fig. 6, is an enlarged perspective detail showing the means for carrying the board laterally from our feed table on to the feed table of the tonguing and grooving machine. Fig. 7, is an enlarged perspective detail of the means for carrying the board laterally at the other end of the machine from the feed table of our attachment 65 to the feed table of the tonguing and grooving machine, and looking from the opposite side of the machine from which Fig. 6 is taken. Fig. 8, is a cross section on line $x'-y'$ Fig. 6.

In the drawings like letters of reference indicate corresponding parts in each figure.

A is a tonguing and grooving machine provided with the usual chain conveyers A' and A² designed to carry the board fed into 75 the machine from each end thereof toward the center and into engagement with the operating mechanism A³.

B is our feeding attachment which is located at one side of the tonguing and 80 grooving machine parallel therewith.

B' is the feeding table of our attachment.

C is the main shaft of the tonguing and grooving machine on which is mounted a sprocket wheel C¹.

C², C³ and C⁴ are shafts mounted in suitable bearings beneath the feed table B'.

C⁵ and C⁶ are sprocket wheels mounted on each end of the shaft C².

C⁷ and C⁸ are sprocket wheels mounted 90 on each end of the shaft C³.

C⁹ and C¹⁰ are sprocket wheels mounted upon the shaft C⁴.

C¹¹ is a sprocket chain forming a driving connection between the sprocket wheel C⁵ and the sprocket wheel C⁵.

C¹² is a sprocket chain which extends around the sprocket wheel C⁶ beneath the sprocket wheel C⁷ and around the sprocket wheel C¹⁰. By this means the sprocket wheel C⁵ and sprocket wheel C⁶ are driven in the direction of arrow and the sprocket wheels C⁷ and C⁸ in the direction of arrow.

C¹³ is an endless feeding chain provided with feeding dogs C¹⁴. The chain C¹³ extends around the sprocket wheel C⁸ at one end and at its opposite end is supported by an idler sprocket pinion C¹⁵, the chain traveling in the direction of arrow see Figs. 3 and 4.

⁵ C¹⁶ is a similar feed chain provided with dogs C¹⁷. The feed chain C¹⁶ extends around the sprocket wheel C⁹ at one end and is supported at its opposite end on the idler sprocket pinion C¹⁸ so as to travel in the direction of arrow see Figs. 3 and 4 or in the opposite direction to the direction of travel of the chain C¹⁶.

¹⁰ D is a guiding strip secured to the feed table B' and extending from a point in proximity to the longitudinal center of the feed table parallel and in close proximity to the outer edge thereof to the end of the table.

¹⁵ D' is a similar strip extending from the center of the table B' in the opposite direction to the opposite end of the table.

²⁰ E is the receiving hopper designed to receive the boards which are to be fed in pairs to the tonguing and grooving machine. The hopper E comprises side portions E', E', one side board E' carried in a stationary position on the feeding table B' and the other in a stationary position on the guiding strip D, adjustable end portion E² and E¹². Each portion E² and E¹² carries a side piece E¹⁸ secured thereto in a stationary position and an adjustable side E⁶.

²⁵ E³ are L-shaped brackets, the upwardly extending arms of the brackets E are secured to the end portions E² and E¹² in proximity to the ends of each of such portions. The lower or horizontal arms of the brackets are provided with longitudinal slots E⁴ (see Fig. 4) through each of which extends a clamping bolt E⁵ holding the portions E² and E¹² longitudinally in position. By this means the length of the hopper may be adjusted to receive and hold a board of ³⁰ the required length.

³⁵ Each portion E² and E¹² is provided with horizontal slots E⁸ located in proximity to one end of the portions E² and E¹². The portions E⁶ are provided with headed pins E⁷ slidably held in the slots E⁸. By ⁴⁰ this means the side portions E⁶ may be adjusted on the end portions E² and E¹² so that the hopper E may be capable of holding boards of various widths in position.

⁴⁵ E¹³ is an opening in the end board E¹² through which the boards are slid into the hopper E.

⁵⁰ E⁹ is a supplemental table on which the boards are piled in pairs. As soon as the top of the pile contained in the hopper comes on a level with the upper surface of the table E⁹ the new pile is pushed forward manually through the opening E¹³ on to the top of the boards contained in the hopper.

⁵⁵ It will be understood that the boards which are fed to the tonguing and grooving machine are to be fed in pairs, that is to say, when it is desired to form boards of a

certain definite width the pairs of boards which are supplied to the hopper may be of any width in relation one to the other but their combined width must be sufficient to form a single board of the desired width ⁷⁰ by the union of the pairs of boards fed to the machine.

⁶⁰ F are a series of leaf springs secured at one end F' in a stationary position to the table B' the free ends of the spring bearing ⁷⁵ toward the guiding strip D.

⁶⁵ F² are similar series of springs located opposite the guiding strip D' and also secured to the table B'. The free ends of the springs F² have a tendency to bear toward ⁸⁰ the strip D'.

⁷⁰ G are a series of parallel boards located at one end of the table B' and flush therewith, such boards extending at right angles across the end of the table and projecting inwardly ⁸⁵ toward the tonguing and grooving machine into close proximity to the feeding conveyer of the tonguing and grooving machine, such boards G being flush with the tongued surface of such feeding conveyer. The boards ⁹⁰ G are spaced a suitable distance apart for a purpose which will hereinafter appear and are suitably connected together at their ends.

⁹⁵ G' is a board secured beneath the boards G and spaced apart therefrom so as to form a horizontal guide-way G'.

¹⁰⁰ G³ is a board slideable in such guide-way being held in position by the guiding strips G⁸ secured thereto at each end and bearing ¹⁰⁵ against both edges of the board G'.

¹⁰⁵ G⁴ are bearing brackets carried by the board G³, such bearing brackets being arranged in pairs.

¹¹⁰ G⁵ are feed dogs provided with trunnions ¹⁰⁵ G⁶ journaled in the brackets G⁴ and tail pieces G⁷ bearing normally against the upper face of the board G³.

¹¹⁵ H is a cross piece provided with notches H', H² and H³ in its lower face, the notches H² and H³ being located opposite intervening spaces between the boards G and the notch H' being located to the outside of the outermost board G. These notches H', H² and H³ form openings through which the ¹²⁰ feed dogs pass when moving in their operative direction.

¹²⁰ H⁴ is a slide piece extending from the cross piece H.

¹²⁵ G¹⁰ is a slot in the center board G.

¹³⁰ G¹¹ is a headed pin extending through the slide piece into the slot G¹⁰.

¹³⁵ I is a swinging arm pivoted at I' to the table B'. The upper end of the arm I is provided with a longitudinal slot I² through which extends the headed pin G¹¹ projecting upwardly from the slide piece H⁴ and downwardly into the slot G¹⁰.

¹⁴⁰ I⁴ is a pressure member connected by a link I⁵ to the arm I.

I⁶ is a leaf spring carried by the pressure member I⁴ and bearing against the arm I.

J is a crank rod mounted on bearings J'.

J² is a lever connected at its upper end 5 with the sliding board G³.

J⁴ is a pitman comprising two portions J⁵ and J⁶, the portion J⁶ being provided with a longitudinal slot J⁷ through which extends clamping bolts provided with nuts J⁸.

J⁹ is a link connected at the lower end of the lever J² to a suitable stationary portion such as the bearing J'.

J¹² is a spring connecting the bars J¹ and J⁶ together to render them readily adjustable longitudinally when the nuts J⁸ are loosened thereby accommodating the lever through to the width of the board fed.

We will now describe the mechanism by which the boards are fed laterally from the opposite end of the machine. K are a series 20 of boards supported similarly to the boards G and provided with a lower board K' forming a side way K² similar to the guideway G². K³ is a cross piece connected to the feed table B' and forming an extension of the side strip D and provided with notches K⁴ and K⁵. K⁶ are feeding dogs similar to the feeding dogs G⁶ as hereinbefore described. L are spring arms connected to the 25 boards K and extending over the cross piece K³ and curving downwardly in proximity to the guiding strip A⁶ of the tonguing and grooving machine passing at their extreme end through the recess A⁷ and provided with 35 up-turned portions L' to which is riveted a closing plate L². The feeding dogs K⁶ are operated by similar mechanism to that described in connection to the feeding dogs G⁶. M is an arm for a purpose which will hereinafter appear.

Having described the principal parts involved in our invention we will briefly describe the operation of the same.

As previously described the boards are piled in pairs in the hopper E. The feeding chains C¹³ and C¹⁶ are then driven in reverse directions so that the dogs of the chain C¹³ engage the board 2 of each pair as indicated by dotted lines in Fig. 4, and the 45 dogs of the chain C¹⁶ engage the opposite edge of the other board 3 of each pair of boards indicated by dotted lines in Fig. 4. By this means the board portion 2 and the 50 board portion 3 are carried in opposite directions into engagement with the leaf springs F and F² which press them against the guide strips D and D' respectively. The chains C¹³ and C¹⁶ carry the boards outwardly to the end of the table B'. The 55 board 2 traveling to the right hand end of the machine engages the pressure bar I⁴ forcing it outwardly against the arm I to an extent in proportion to its width, the arm I carrying the cross piece H a relative distance so as to allow the outer edge of the

board 2 to slide past and against the inner edge of the cross piece H. It will be understood that the mechanism of our feeding device is so timed that the board when carried to the position above described is in exactly 70

the right position to be engaged by the feeding dog 4 of the tonguing and grooving machine when the board has been carried laterally as hereinafter described. The crank J operates through the lever J² to draw the 75 cross board G³ carrying the dogs G⁵ forwardly. The dogs G⁵ pass through the notches H¹, H² and H³ and engage the board 2 which is carried forwardly on to the feeding conveyer of the tonguing and grooving 80 machine. As the feeding dogs G⁵ traverse the space between the cross piece H and the feeding conveyers of the tonguing and grooving machine another board 2 is carried into place.

During the reverse movement of the feeding dogs G⁵ the upper faces of such dogs engage with the new board 2 and are tilted slightly downwardly so as to pass beneath the same to their normal position. The board portion 3 which passes to 90 the left hand end of the machine passes along in close proximity to the guiding strip D until they are in the lateral feeding position in front of the notches K⁴ and K⁵, the board being held down in this position by 95 the arm M. The dogs K⁶ then operate to carry the board laterally. During such lateral movement the board engages the downwardly curved portions of the spring arms L carrying such portions upwardly and 100 thereby raising the plate L² carried thereby above the top of the recess A⁷ holding it in this position until the board has passed such plate. Immediately the board has passed the plate the arms force the plate 105 downwardly in front of the recess to close the same, the board being then held against such plate by the leaf springs O carried by the bar O' secured to the feeding table of the tonguing and grooving machine.

In order to allow of different width of boards being fed we provide a laterally sliding piece Z which supports the conveyer chain C¹⁶ and guide strip D. The piece Z is held on guide bars which support an outer 115 stationary retaining strip Z² between which and the body of the table the piece Z has movement. The gears C⁹ and C¹⁸ are secured to their supporting shafts by set screw so as to be adjustable with the 120 pieces Z.

Suitable clutches may be employed by which the conveyers of the tonguing and grooving machine and the conveyers of the attachment may be alternately thrown in 125 and out of gear.

From this description it will be seen that we have devised a very simple feeding attachment for a tonguing and grooving machine by which the boards are carried from 130

their central position to the ends of the machine and are then fed laterally thereinto.

What we claim as our invention is:

1. The combination with the tonguing and grooving machine provided with the usual inwardly feeding longitudinal end conveyors, of a feeding device designed to feed a board in either direction from a point intermediate of the length of the tonguing and grooving machine and parallel thereto to the end of such machine and on to the longitudinal conveyors thereof, as and for the purpose specified.

15 2. The combination with the tonguing and grooving machine provided with the usual end conveyors designed to feed a board inwardly toward the center of the machine, of a feeding attachment designed to feed a board in either direction from a point intermediate of the length of the machine to each end thereof and supplemental means for moving each board laterally into the conveyors of the tonguing and grooving machine, as and for the purpose specified.

25 3. A feeding attachment for tonguing and grooving machines comprising a feed table, a board receiving hopper mounted thereon and designed to contain a series of boards arranged horizontally in pairs, of an endless conveyor extending under each board of each pair, means for driving the conveyors in reverse directions so as to carry the one board longitudinally in one direction and the other board longitudinally in the 30 opposite direction, as and for the purpose specified.

4. A feeding attachment for tonguing and grooving machines comprising a feed table, a board receiving hopper mounted thereon and designed to contain a series of boards arranged horizontally in pairs, of an endless conveyor extending under each board of each pair, means for driving the conveyors in reverse directions so as to carry the one board longitudinally in one direction and the other board in the opposite direction and mechanism for carrying the boards laterally from the ends of the longitudinal conveyors, as and for the purpose specified.

50 5. A feeding attachment for tonguing and grooving machines comprising a feeding table adapted to lie parallel with the tonguing and grooving machine, guiding strips extending each way from the center of the feed table in proximity to the opposite edges thereof, an endless conveyor traveling in proximity to the inner edge of each guide strip and resilient means for holding the boards carried by the conveyors against the guide strips during their travel from end to end of the guide strips, as and for the purpose specified.

60 6. A feeding attachment for tonguing and grooving machines comprising a feeding table adapted to lie parallel and flush with

the feed table of the tonguing and grooving machine, a feed hopper carried by the table of the feeding attachment intermediate of its length and designed to contain boards arranged in pairs, and means for carrying one board of each pair longitudinally in one direction and the other board of each pair longitudinally in the opposite direction and transverse slidable dogs located at the end of each longitudinal conveyor and designed to engage the end of the board to carry it laterally on to the feeding conveyor of the tonguing and grooving machine, as and for the purpose specified.

7. In a feeding attachment for tonguing and grooving machines, the combination with the main feeding table thereof and a longitudinal board conveyor carried thereby, of a supplemental feeding table located at the end of the aforesaid table and arranged at right angles thereto and flush therewith, feeding dogs carried by the supplemental table, means for reciprocating the dogs longitudinally of such supplemental table, a notched cross bar slidably carried by the supplemental table and through the notches of which the dogs are designed to pass, and means operated by the approaching board for adjusting the cross bar on the supplemental table to allow a board of any width to pass on to the supplemental table in front of the cross bar and in contact therewith, as and for the purpose specified.

8. In a feeding attachment for tonguing and grooving machines, the combination with the main feeding table, of a supplemental feeding table located at the end of the main feeding table at right angles thereto and flush therewith, feeding dogs slidably carried by the supplemental table and adapted to travel longitudinally thereof, a notched cross bar slidably carried by the supplemental table and through the notches of which the dogs are designed to pass, a supplemental arm pivotally mounted upon a suitable support at one end and pivotally connected to the cross bar at the opposite end, a spring pressed engaging bar set at angle to the longitudinal conveyors and with the end of which the feed board is designed to engage and a link connection between such bar and the supplemental arm connected to the aforesaid notched cross bar, as and for the purpose specified.

9. In a feeding attachment for tonguing and grooving machines, the combination with a feeding table thereof and a longitudinal board conveyor carried thereby and the conveyor guiding strip of the tonguing and grooving machine having an orifice therein adapted to allow the passage of boards therethrough on to the conveyor of the tonguing and grooving machine, of a supplemental feeding table located at the end thereof at right angles thereto and flush

therewith, a guiding strip extending longitudinally of the main feeding table in proximity to the conveyers and provided with an extension extending over the supplemental table and having notches therein in the inner face thereof, reciprocating feeding dogs carried by the supplemental table and moving longitudinally thereof and designed to engage the side of the board fed from the longitudinal conveyer to pass the boards laterally through the aforesaid orifice of the tonguing and grooving machine, a temporary closing plate for such admission orifice adapted to be raised by the passage of the boards therethrough and to then drop between the boards so passed and the orifice, and resilient pressure means adapted to be carried by the tonguing and grooving machine to force said board against such plate, as and for the purpose specified.

10. In a feeding attachment for tonguing and grooving machines, the combination with the side guiding strip of a tonguing and grooving machine having an admission orifice extending therethrough, of a feeding attachment provided with a feeding table, a feeding conveyer extending longitudinally thereof, a supplemental feeding table extending at right angles thereto and flush therewith, reciprocating feeding dogs carried by the table, a side guiding strip for the longitudinal conveyer having an extension having notches on its under face through which the dogs are designed to pass, cam formed curved leaf-springs secured to the supplemental table and extending over the guiding strip extension and downwardly in proximity to the guiding strip of the tonguing and grooving machine and through the orifice thereof, and a closing plate for the orifice carried by the ends of the springs, and spring pressure means adapted to force the boards passed through the orifice past the closing plate against such plate, as and for the purpose specified.

20. In a feeding attachment for tonguing and grooving machines, the combination with the side guiding strip of a tonguing and grooving machine having an admission orifice extending therethrough, of a feeding attachment provided with a feeding table, a feeding conveyer extending longitudinally thereof, a supplemental feeding table extending at right angles thereto and flush therewith, reciprocating feeding dogs carried by the table, a side guiding strip for the longitudinal conveyer having an extension having notches on its under face through which the dogs are designed to pass, cam formed curved leaf-springs secured to the supplemental table and extending over the guiding strip extension and downwardly in proximity to the guiding

strip of the tonguing and grooving machine and through the orifice thereof, and a closing plate for the orifice carried by the ends of the springs, as and for the purpose specified.

11. In a feeding attachment for tonguing and grooving machines, the combination with the side guiding strip of a tonguing and grooving machine having an admission orifice extending therethrough, of a feeding attachment provided with a feeding table, a feeding conveyer extending longitudinally thereof, a supplemental feeding table extending at right angles thereto and flush therewith, reciprocating feeding dogs carried by the table, a side guiding strip for the longitudinal conveyer having an extension having notches on its under face through which the dogs are designed to pass, cam formed curved leaf-springs secured to the supplemental table and extending over the guiding strip extension and downwardly in proximity to the guiding strip of the tonguing and grooving machine and through the orifice thereof, and a closing plate for the orifice carried by the ends of the springs, and spring pressure means adapted to force the boards passed through the orifice past the closing plate against such plate, as and for the purpose specified.
